UNITED STATES PATENT OFFICE.

JAMES B. HAMMOND, OF NEW YORK, N. Y.

TYPE-WRITER SHUTTLE AND DRIVING MECHANISM THEREFOR.

No. 825,967.

Specification of Letters Patent. Patented July 17, 1906.

Application filed October 21, 1904. Renewed June 15, 1906. Serial No. 321,914.

To all whom it may concern:

Be it known that I, JAMES B. HAMMOND, a citizen of the United States, residing at New York city, New York, have invented certain new and useful Improvements in Type-Writer Shuttles and Driving Mechanism Therefor, of which the following is a specification.

My invention relates to type-writers of the 10 class known as the "Hammond," and concerns particularly an improved form of shuttle and means for driving the same, whereby lightness of the parts is secured and rapidity of operation is permitted.

15 The invention consists in the features and combination and arrangement of parts hereinafter described, and particularly pointed out in the claims.

In the accompanying drawings, Figure 1 is 20 a plan view of a shuttle and its driving mechanism, said shuttle being shown in proper relation to the hammer. Fig. 2 is a central vertical sectional view through the shuttle and its driving mechanism. Fig. 3 is a detail view of means for driving the shuttle.

In the drawings, 1 is the anvil, of ring form, supported upon a post 2, which holds the said anvil against turning movement. The improved form of shuttle consists of a ring of 30 hard rubber which fits against the outer face of the anvil and is provided with a flange 4, extending entirely around the upper edge of the shuttle and projecting inwardly therefrom. This flange rests upon the upper edge 35 of the anvil, and thus supports the ring-shaped shuttle. The shuttle is made very thin to secure lightness and to allow rapidity of operation, and the flange 4, serves as a strengthening means for the shuttle. I also 40 utilize the flange as the means of connection with the shuttle-arm: This shuttle-arm is shown at 5 and includes a vertical portion, the upper end of which passes through an eyelet or bushing 6, embedded in the hard- 45 rubber flange 4 of the shuttle, the said bushing or eyelet being riveted to the flange. The said arm also has a horizontal portion provided with a sleeve 7, fitting around the anvil-post, and this sleeve also carries the stop- 50 arm 8, extending forwardly and adapted to be arrested by striking the vertically-movable stop-pins, as is well known in the Hammond machine.

The shuttle is driven from drivers 9 in a 55 manner generally similar to that known in this class of machines; but in order to secure

rapidity of operation I interpose speed-dogs or supplemental driving-arms 10 between the drivers 9 and the shuttle-arm 5. These speed-dogs are carried each by a sleeve 11, 60 which extends one within the other, and both lie within the hub or sleeve 7 of the shuttle-arm.

The speed-dogs or supplemental drivers are adapted to swing in a horizontal plane and 65 are provided with pins 13, adapted to be engaged by the teeth 14 of the main drivers 9. These speed-dogs are provided with notches 15 and are adapted to engage a pin 16 on the shuttle-arm to swing the same in either one 70 direction or the other, according to which speed-dog is operated. The speed-dogs are of course capable of movement independent of each other, and, supposing one of them—for instance, the one at the right of Fig. 1—to 75 be swung toward the left and the pin 16 to be engaged thereby and the shuttle moved leftward, as soon as the key is released the operator can immediately strike a key on the left of the keyboard and the left-hand speed-dog will immediately begin to swing and follow up the movement of the shuttle toward 80 the right until the proper position is reached and the stop-arm strikes the stop-pin.

In certain machines of this type it has been 85 necessary after depressing, for instance, a key on the right of the machine to allow the shuttle-arm and shuttle to regain their central position before a key on the left could be struck; but with the improved arrangement 90 of driving mechanism in which the speed-dogs are employed it is not necessary to wait until the shuttle and shuttle-arm have been returned to normal or central position before striking the key to move the shuttle in the opposite direction from that in which it was formerly moved, for it will be obvious that by reason of the employment of the speed-dog and the connection between the main driving-arms and the said dogs one dog may advance 95 simultaneously with the return movement of the other dog, and thus the shuttle may continue to move past its central position under the pressure of the key last struck.

In order to secure an easy movement of 105 the shuttle, ball-bearings α may be provided between the overhanging flange thereof and the anvil, and these ball-bearings may be located in pockets or a groove in the upper edge of the anvil, where they may be held in 110 any suitable manner. The shuttle also may have rolling contact at the points 17, such

contact being provided by means of rollers 18, journaled in the anvil and having their outer peripheries bearing upon the inner side of the shuttle.

5 From the above it will be seen that I provide a shuttle of hard rubber which is very thin and strengthened by the flange formed integrally therewith and that I utilize a portion of the film-like shuttle itself for the connection with the shuttle-arm.

I do not limit myself to the precise connection shown, as this might be varied; but I prefer in any case to utilize a projecting portion of the hard rubber from the shuttle-ring 15 to serve as a driving part between the said shuttle and the shuttle-arm.

The shuttle may carry different fonts of type, and these may be brought into use simply by lifting the shuttle and turning it until 20 the proper font or set of type is in position for printing, when the shuttle is reengaged with its arm 5. The flange of the shuttle is therefore provided with a series of eyelets or bushings 6 for receiving the shuttle-arm.

25 I claim as my invention—

1. In combination in a type-writer, an anvil in the form of a complete ring, a shuttle also of complete ring form surrounding the anvil, and provided with a flange at its upper 30 edge resting upon the upper edge of the anvil, said anvil having working within it a shuttle-arm in connection with a part of the said flange, substantially as described.

2. In combination in a type-writer, an anvil, a shuttle of complete ring form of hard rubber having an integral flange extending around the same to serve as a strengthening means, said shuttle being open vertically within the flange, substantially as described.

3. In combination, in a type-writer, an anvil, a ring-shaped shuttle having an integral projecting portion of hard rubber at the extreme upper edge and a shuttle-arm engaging said portion.

45 4. In combination, in a type-writer, an anvil, a ring-shaped shuttle having a flange at its extreme upper edge overhanging the anvil, and a shuttle-arm connected with the said flange, substantially as described.

5. In combination with an anvil, a shuttle 50 in the form of a complete ring surrounding the anvil and provided with a flange at its upper edge extending continuously about the shuttle and overlying the upper edge of the anvil, said anvil having working within it, a shuttle-arm in connection with a part of the said flange and antifriction-balls arranged beneath the overlying flange of the shuttle and supported by the top edge of the anvil.

6. In combination with a shuttle, a shuttle-arm, drivers one for each side of the shuttle, and the speed-dogs or supplemental drivers one for each side of the shuttle interposed between the main drivers and the shuttle-arm, substantially as described. 65

7. In combination, an anvil, a shuttle, a shuttle-arm, a pair of speed-dogs or supplemental drivers arranged to swing around the anvil-post and main drivers for operating the supplemental drivers, substantially as de- 70

8. In combination, the anvil, a shuttle, a shuttle-arm, a pair of speed-dogs arranged to swing about the anvil-post, a pin on the shuttle-arm to be engaged by the speed-dogs, pins 75 on the speed-dogs and drivers having toothed portions to engage the pins, substantially as described.

9. In combination, a shuttle in one piece to swing both ways to carry the type to the 80 printing-point, speed-dogs arranged normally in divergent relation, and adapted to drive the shuttle, said speed-dogs moving about the axis of the shuttle, and main drivers for operating the speed-dogs, sub- 85 substantially as described.

10. A type-writer shuttle of circular form, having a continuous flange extending about the same, the space within the inner edge of the flange being free vertically, substantially 90 as described.

In testimony whereof I affix my signature in presence of two witnesses.

JAS. B. HAMMOND.
